UNITED STATES PATENT OFFICE.

JAMES WOOD, OF NOROTON, CONNECTICUT.

STOVE.

SPECIFICATION forming part of Letters Patent No. 742,108, dated October 20, 1903.

Application filed February 18, 1903. Serial No. 143,939. (No model.)

To all whom it may concern:

Be it known that I, JAMES WOOD, a citizen of the United States, and a resident of Noroton, in the county of Fairfield and State of Connecticut, have invented a new and Improved Stove, of which the following is a full, clear, and exact description.

The prime feature of this invention is a certain improved construction involving an air-jacket surrounding the stove, so that the cold air entering at the bottom may be heated by contact with the walls of the stove and discharged from the top of the jacket to heat the surrounding air or be carried off to another apartment of the building in which the stove is placed.

The invention also involves a novel air-feeding attachment for the stove, which allows me to introduce pure atmospheric air into the combustion-chamber of the stove at will, thus bringing about thorough combustion of the escaping gases.

This specification is an exact description of two forms of my invention, while the claims define the actual scope thereof.

Reference is to be had to the accompanying drawings, forming a part of this specification, in which similar characters of reference indicate corresponding parts in all the views.

Figure 1 is a perspective view of the invention. Fig. 2 is an enlarged vertical section thereof. Fig. 3 is a section on the line 3 3 of Fig. 2. Fig. 4 is a section on the line 4 4 of Fig. 2, and Fig. 5 is a horizontal section of a modified form of the invention.

a indicates the body of the stove, which in itself does not differ from the usual cylinder-stove, it being provided with a cap *a'*, a feeding-door *a''*, an ash-door *a'''*, and a base *a''''*, all of any desired form.

b indicates the jacket, which extends from directly above the base *a''''* outward from the sides of the stove and thence upward parallel therewith until the cap *a'* is reached. The jacket *b* turns in at its front edges, as indicated at *b'*, to meet the walls *a* at each side of the door *a''*. This forms an inclosed space surrounding the body of the stove and heated by radiation from said walls. As shown in

Figs. 1, 2, 3, and 5, air-inlet pipes *c* are provided at the lower portion of the jacket, and at the upper portion of the jacket air-outlet

pipes *c'* are arranged. In Figs. 1, 2, and 4, *d* indicates the smoke pipe or flue, which passes from the stove in the usual manner. If desired, the air may be drawn not merely from the room in which the stove is placed, but from outside of the house, and to do this a curved tube-header *e* may be provided to communicate with the tube *c* and with the atmosphere by means of a tube *e'*, all of which is shown in Fig. 5.

To facilitate the complete combustion of the gases escaping from the fuel, I provide in the upper rear portion of the stove-body *a* a vertically-disposed baffle-plate *f*, fastened to the walls of the stove by means of brackets *f'*. From this baffle-plate *f* a tube *f''* projects forward, the plate *f* being perforated at the rear end of the tube, so as to permit the air to pass from said tube through perforations at the back of the baffle-plate. The tube *f''* projects through the front wall of the stove, and in this tube is fitted a telescopic tube *f'''*, having a handle *f''''* at its front end and a series of perforations *f'''* adjacent to said end, it being noted that the said baffle-plate also serves practically as a support for the inner end of said tube *f''* within the upper part of the combustion-chamber of the stove. When the tube *f'''* is pushed inward for its whole length, the openings *f'''* will be covered and the tube *f''* will be closed. When, however, the tube *f'''* is drawn out, as in Fig. 2, there is a clear passage opened through the sections *f'''* and *f''* to the space back of the baffle-plate *f*, thus supplying fresh air to this space and supporting the entire combustion of the combustible substances in these gases. This arrangement for admitting fresh air also increases the draft through the flue *d*, and thus prevents any of the gases from the stove escaping into the room or building in which the stove is placed.

By means of my invention a maximum degree of heat may be drawn from a minimum supply of fuel, since the jacket *b* and its appurtenances provide for the utilization of practically all of the heat developed, while the air-supply devices *f'' f'''* enforce complete combustion of the fuel.

Various changes in the form, proportions, and minor details of my invention may be resorted to at will without departing from the

spirit and scope thereof. Hence I consider myself entitled to all such variations as may lie within the intent of my claims.

From the foregoing it will be noted that my improvements constitute practically an attachment which may be applied to many forms of ordinary stoves at present in use substantially without any alteration thereof.

Having thus described my invention, I claim as new and desire to secure by Letters Patent—

1. The combination with a stove having a door in the front thereof, of a jacket surrounding the rear and sides of the stove and having inturned edges at its top, bottom and front, thus forming a complete inclosure surrounding the stove, said jacket having an air-inlet opening at its bottom and an air-outlet opening at its top, tubes projecting from the jacket at said openings, a tube-header encircling the stove and communicating with the lower series of tubes, and an air-pipe extending from the header.

2. The combination with a stove, of a vertically-disposed baffle-plate located within the combustion-chamber thereof, in proximity to

the exit of said chamber, an air-supply tube leading from the exterior of the stove and supported at its inner end by said plate, the latter being perforated at the point of such support, and means for controlling the passage of air through said tube to the rear of the plate.

3. The combination with a stove, of a vertically-disposed baffle-plate located within the combustion-chamber thereof, in proximity to the exit of said chamber, an air-supply tube leading from the exterior of the stove, and supported at its inner end by said plate, the latter being perforated at the point of such support, and means for controlling the passage of air through the tube to the rear of the plate, said means comprising a perforated tube slidable with reference to the first-named tube.

In testimony whereof I have signed my name to this specification in the presence of two subscribing witnesses.

JAMES WOOD.
